L. M. HULL

RADIOTELEGRAPH TRANSMITTING SYSTEM

Filed Oct. 16, 1920

Inventor
Lewis M. Hull

UNITED STATES PATENT OFFICE.

LEWIS M. HULL, OF CHEVY CHASE, MARYLAND.

RADIOTELEGRAPH TRANSMITTING SYSTEM.

Application filed October 18, 1920. Serial No. 417,405.

To all whom it may concern:

Be it known that I, LEWIS M. HULL, a citizen of the United States, residing at Chevy Chase, in the county of Montgomery and State of Maryland, have invented new and useful Improvements in Radiotelegraph Transmitting Systems, of which the following is a specification.

This invention relates to improvements in radio frequency systems comprising tuned oscillatory circuits, and in particular to systems in which high-frequency alternating-current power is amplified by means of three-electrode electron-tube amplifiers. One object of my invention is to simplify the oscillatory circuits which are associated in such systems with electron tubes, by eliminating one of the circuit elements previously used. Another object resides in the provision of means for increasing the range of resonant frequencies obtainable in high-frequency generating systems employing an electron-tube amplifier of massive construction whose intra-electrode capacities are large.

An essential part of every radio-frequency system is an oscillatory circuit comprising the inductive and capacitive elements necessary for establishing in that circuit a condition of resonance to oscillations of a given frequency. In systems using an electron tube associated with such an oscillatory circuit I have found that the effective capacity existing between grid and cathode of the tube will at radio frequencies be of sufficient magnitude to be an important factor in establishing the resonance condition. In fact, by connecting the grid-cathode circuit of an electron tube directly in the oscillatory circuit, the separate condenser which would otherwise be necessary may be eliminated entirely, and the effective capacity reactance of this grid-cathode circuit substituted instead. Besides the advantage of simplification of the oscillatory circuit, other benefits accrue from the elimination of the condenser previously employed.

Owing to the presence of permanent and irreducible capacities existing between all

the electrodes of a three-electrode tube the effective input capacity acting between the grid and cathode of said tube may be greatly in excess of the self capacity existing between these electrodes alone. This capacity cannot be eliminated without eliminating the electron tube entirely, and affects or determines both the magnitude of the current and the condition of resonance in the associated oscillatory circuit. By means of my invention this unavoidable capacity is transformed from a wasteful absorber of electrical power into an essential tuning element, and its use as a tuning element allows a reduction in the minimum capacitive reactance attainable in the oscillatory circuits, thus increasing the maximum frequency to which these circuits are resonant.

The latter object of my invention is of particular interest and importance in the case of radio transmitting systems. For purposes of illustration I have shown my invention as being embodied in a transmitter comprising an electron-tube generator of radio-frequency currents, in such combination with one or more electron-tube amplifiers that the effective input capacity of the amplifying system operative between grid and cathode of the electron-tube amplifier, forms the essential capacity element of the tuned oscillatory circuit of said radio-frequency generator. The output circuit of the amplifying system is operatively coupled with a transmission circuit for radiating the radio-frequency waves produced by the generator.

The single figure of the drawing represents the circuit connections of a transmitting system comprising my invention.

In this figure an electron tube generator is shown at (1), consisting of the usual plate, grid, and incandescent cathode. (6) is a telegraphic key, (17) is a variable self-inductance, and (16) is a battery. (2) is a second electron tube, of suitable characteristics to serve as an amplifier of high-frequency currents; (10) is a battery for heating the cathode of said amplifier; (5) 100

is a direct-current generator; (12) and (8) are self-inductance coils possessing, in addition, mutual inductance; (7) and (9) are, respectively, the aerial and ground portions 5 of a transmission circuit of the open antenna type.

Electrical power is supplied to the radio-frequency generator (1) from battery (16). The high-frequency currents generated by 10 this tube may be interrupted, for the purpose of radio-telegraphic signaling, by the key, (6). The electron-tube amplifier (2) is coupled to the antenna or radiating system (7), (8), (9), by the mutual inductance 15 between the coils (12) and (8); the plate circuit of this amplifier is supplied with power by the direct-current generator (5). A tuned oscillatory circuit consisting of capacity and inductance elements connected in 20 parallel is essential to the operation of the generator (1). This circuit is provided by the self-inductance coil (17) and the effective input capacity between the grid and cathode of the amplifier (2). The frequency 25 of the oscillatory currents maintained by the generator (1) is determined by the self-inductance of this coil (17) and the effective input capacity of the amplifier (2). When the system is in operation a high-frequency 30 alternating current is maintained by the generator (1) in the oscillatory circuit composed of coil (17) and the grid-cathode capacity of amplifier (2). As a result of this 35 current there is impressed between grid and cathode of amplifier (2) a high-frequency alternating voltage. This serves as an exciting voltage and produces in the tuned output circuit of the amplifier, comprising antenna (7), (8), (9), and coupling coil 40 (12), a high-frequency current of the same form and frequency as that supplied by the generator, but of much greater amplitude. The additional power necessary for this 45 magnified high-frequency current is drawn in the usual way from the direct-current generator (5). By means of this arrangement the amplifier (2) is thus made to perform a two-fold function: it provides capacity reactance necessary for the operation 50 of the generator (1), and amplifies the radio-frequency alternating-current power supplied to it from the generator (1), producing in the antenna alternating currents 55 of greater electrical power. In practice the frequency of the current supplied by the generator is made equal to the resonant frequency of the antenna, which in effect comprises a tuned circuit between the inductance (8) and the capacity between aerial 60 (7) and ground (9).

In the species of my invention shown by this diagram the generating circuit used with the generator (1) is of the type known as the "reversed feedback" circuit. But it 65 is immaterial which of the various types of

electron-tube generating circuit is employed to excite the amplifier. Each of the several well-known generating circuits requires a periodic or resonant mesh containing a capacity element. The invention discloses 70 a novel and economical method for providing this capacity and simultaneously amplifying the resulting radio-frequency alternating current, regardless of the type of generating circuit employed to produce this current. 75

Although I have described my invention in detail only with reference to specific transmitting circuits, the utility of the general principle involved, that of tuning an 80 oscillatory circuit by making use of the intra-electrode capacity of an electron tube, it is not limited to such systems. Wherever an oscillatory circuit is operatively coupled or connected with an electron tube for purposes of amplification of the radio-frequency currents flowing in that circuit, my invention constitutes an improvement over existing systems inasmuch as it provides the capacity element essential to the oscillatory 85 circuit, by the useful employment of the inherent intra-electrode capacities of the electron tube, which in existing systems are not only useless, but frequently detrimental to 90 efficient operation of the apparatus. 95

What I claim is:

1. A system for the radiation of electric waves comprising a transmission circuit, an electron-tube amplifier whose plate-cathode circuit is operatively coupled to said transmission circuit, and a self-excited electron-tube generating system so connected to the grid-cathode circuit of said amplifier that the inherent intra-electrode capacity of 100 said grid-cathode circuit furnishes capacity reactance for the operation of said self-excited electron-tube generating system. 105

2. A system for the radiation of electric waves comprising a transmission circuit, an electron-tube amplifier whose plate-cathode circuit is operatively coupled to said transmission circuit, and a self-excited electron-tube generating system so connected to the grid-cathode circuit of said amplifier that the inherent intra-electrode capacity of 110 said grid-cathode circuit furnishes capacity reactance essential to the operation of said self-excited electron-tube generating system, and means for interrupting the plate-cathode circuit of said generating system for the transmission of radiotelegraphic signals. 115

3. The system defined by claim 1, in which the self-excited electron-tube generating system contains a self-inductance coil connected in the grid-cathode circuit, and a second self-inductance coil connected in the plate-cathode circuit, but possessing mutual inductance with the first, said second inductance coil being also connected in parallel 120 with the capacity reactance furnished by the 125 130

inherent intra-electrode capacity of the grid-cathode circuit of the electron-tube amplifier.

4. The system defined by claim 1, in which the self-excited electron-tube generating system contains a closed plate-cathode circuit, a closed grid-cathode circuit, and a periodic circuit operatively coupled to said plate-cathode and grid-cathode circuits, said peri-

odic circuit consisting of a self-inductance 10 coil connected in parallel with the capacity reactance furnished by the inherent intra-electrode capacity of the grid-cathode circuit of the electron-tube amplifier.

In witness whereof I hereunto subscribe 15 my name this 11th day of October, A. D. 1920.

LEWIS M. HULL.
